L. LEWIS & T. E. TAGGART.

HYDRAULIC MOTOR.

APPLICATION FILED FEB. 16, 1914.

1,168,317.

Patented Jan. 18, 1916.

UNITED STATES PATENT OFFICE.

LLEWELYN LEWIS AND THOMAS E. TAGGART, OF COLUMBUS, OHIO, ASSIGNEES TO THE AMERICAN WATER MOTOR COMPANY, OF COLUMBUS, OHIO, A CORPORATION OF OHIO.

HYDRAULIC MOTOR.

1,168,317.

Specification of Letters Patent. Patented Jan. 18, 1916.

Application filed February 16, 1914. Serial No. 818,843.

To all whom it may concern:

Be it known that we, LLEWELYN LEWIS and THOMAS E. TAGGART, citizens of the United States, residing at Columbus, in the county of Franklin and State of Ohio, have invented a certain new and useful Improvement in Hydraulic Motors, of which the following is a specification.

The object of this invention is to provide an improved hydraulic motor in which metallic closures for valves are avoided and softer material, such as leather employed.

A further object is the provision of a construction in which the same spring is utilized for shifting the valve structure at the end of the stroke in each direction.

Further objects are the simplification and the increasing effectiveness of the construction.

20 The invention is embodied in the example herein shown and described, the features of novelty being pointed out in the claims.

In the accompanying drawings, Figure 1 is a central longitudinal sectional view including the intake and exhaust pipes. Fig. 2 is a partial cross section on the line *w-w* Fig. 1, looking toward the right. Fig. 3 is a similar section on the line *x-x* Fig. 1, looking toward the left. Fig. 4 is a like section on the line *y-y* Fig. 1, looking toward the right. Fig. 5 is a cross section on the line *z-z* Fig. 1, looking toward the left.

In the views 10 designates the cylinder, 35 having heads 11 and 12. Within the cylinder is a piston 13 consisting of a hollow metallic structure having inner and outer annular walls forming an annular chamber that is divided into two compartments or 40 chambers 15 and 16 by radial walls 14, 14^a. For the purpose of illustration and description the chamber 15 may be treated as the intake chamber in which case the chamber 16 is the exhaust. The central opening of the 45 piston constitutes a seat for a reciprocating valve. The intake chamber 15 has connected with it a tube 17 that extends through the cylinder head 11 and the exhaust chamber 16 has connected to it a tube 18 that also 50 extends through said head. The said tubes reciprocate with the piston.

In the central opening of the piston is a valve, the body of which, consists of two tubular parts 19 and 20 connected by a 55 coupling 21, cup leathers 22 and 22^a being

interposed between the ends of the coupling and shoulders on the tubular parts 19 and 20. The opposite ends of the valve body where they project beyond the seat are threaded and carry valves 23 and 24 to open 60 and close the ports 25 and 26 respectively to the exhaust chamber. These valves are faced with leather as seen at 23^a and 24^a. Within the hollow valve body are headed pins 27 and 28 having their shanks normally projected beyond the ends of the valves by a spring 29 lying within the valve body between the heads of said pins.

30 and 31 are slot ports from the intake chamber 15. These ports are alternately 70 opened and closed by the cup leathers 22 and 22^a. The ends of the tubular valve body are of smaller diameter than the valve seat but those ends are provided with radial lugs such as seen at 32 spaced apart to provide 75 ample passages for water from port slot 30 or 31 into the adjacent end of the cylinder. Secured to the rim of the piston by means of a ring 33 are cup leathers 34. The ring 33 has formed with it a yoke 35 to which latter is connected a work rod 36 that extends through a stuffing box 12^a on the cylinder head 12. Located on the yoke 35 is a bumper plate 37 having pins 38 that pass through 80 holes in the yoke 35 in position to abut 85 against the cylinder head 12.

The operation is this: In the position of the parts illustrated in Fig. 1 the piston is moving from left to right, the direction of the flow of water pressure being indicated 90 by the arrows. The exhaust port 25 is closed while the exhaust port 26 is open. Water flowing through the slot port 30 passes into the cylinder at the left hand side of the piston and exerts its pressure on the piston 95 moving it to the right and forces the water in the right hand end of the cylinder through the port 26 into the exhaust chamber 16 of the piston and thence out pipe 18. In time the pins 38 of the bumper plate 100 strike the cylinder head 12 and the bumper plate is held stationary while the piston continues to move to the right. The advancing pin 28 next strikes the bumper plate compressing the spring 29. Eventually the 105 valve body strikes the bumper plate and as the piston still continues to advance the valve is by the impact with the cylinder head shifted with reference to the piston so that the slot port 31 is opened and the slot 110

port 30 closed. The pressure of the spring insures a complete and prompt shifting of the valve body. The shifting of the valve also causes the closing of the exhaust port 26 by the valve 24. When the valve is thus shifted the water flows into the right hand end of the piston thereby exerting its pressure on the right hand side of the piston which is then moved toward the left. The 10 operation in moving the piston to the left is the same as that first described except that there being no need for a bumper plate at that end of the cylinder, the pin 27 and the corresponding end of the valve strike the 15 cylinder head 11 directly. When the valve moving toward the left strikes the cylinder head 11 the parts again assume the position shown in Fig. 1 and the operation first described is repeated.

20 What we claim is:

1. In a hydraulic motor, a cylinder, a piston provided with an intake chamber, an exhaust chamber and a seat for a reciprocating valve, a hollow reciprocating valve in said seat adapted to open and close the ports from the intake chamber, said chambers

having suitable ports, valves to open and close the ports to the aforesaid exhaust chamber, pins in said reciprocating valve and a spring between said pins to hold the 30 same projected beyond the ends of the valve.

2. In a hydraulic motor, a cylinder, a piston therein provided with an intake, an exhaust chamber and a seat for a reciprocating valve, said exhaust chamber having ports 35 leading thereto from the opposite sides of the piston and said intake chamber having ports leading therefrom into the valve seat, a hollow reciprocating valve in said seat adapted to open and close the ports from the 40 intake chamber, and valves on the end of the reciprocating valve adapted to open and close the ports to the aforesaid exhaust chamber, pins in said hollow reciprocating valve and a spring between said pins to hold the 45 same projected beyond the ends of the valve.

LLEWELYN LEWIS.
THOMAS E. TAGGART.
